UNITED STATES PATENT OFFICE.

FREDERICK J. WERMES, OF NORWOOD, OHIO, ASSIGNOR TO S & W MACHINE COMPANY, OF CINCINNATI, OHIO, A PARTNERSHIP COMPOSED OF FREDERICK J. WERMES AND ROBERT H. STELTENPOHL.

BENDING MACHINE.

Application filed December 26, 1925. Serial No. 77,760.

My invention belongs to that class of bending machines employed to bend electrotype, lead, or metal plates into a curved or convex form.

5 Said plates, when made, are usually flat and must be bent into a curved, concave or curvilinear shape, so that they can be used for printing when placed on a rotary printing press.

10 Much trouble and inconvenience results in attempting to bend these plates so that the curve thereof will be even, uninterrupted and unbroken by flat or similar surfaces or spots, in other words, in order to do good

15 printing, the curved plates must not have an undulated surface, but must be evenly curved in order to do first class printing.

One of the salient features of my invention consists in providing a large forming 20 roll and a series of supporting rolls, and placing floating rolls between them, and in further placing the floating rolls in close contiguity by closeness of centers thereof, allowing no play, and placing the desired 25 curvature on the plate at the beginning of its passage through the rolls and continuing to so uniformly bend the same, (the plate) throughout its extent, so that the plate is evenly bent throughout its entire surface, insuring first class printing.

30 The various features of the invention and their advantages will readily become apparent from reading the following specification:

35 In the accompanying drawing, forming part of this specification:

Fig. 1, is a front elevation, partly broken away and in section to illustrate construction;

40 Fig. 2, is an end view of machine shown in Fig. 1;

Fig. 3, is a plan view of the machine with the adjusting screws in section;

45 Fig. 4, is a section taken on line 4—4 of Fig. 1, showing the position of the rolls only, and

Fig. 5, is a section taken on line 5—5 of Fig. 1, showing the position of the rolls only.

50 In carrying out my invention, I provide a frame made up of the ends 1 and 2, sup-

ported on runners 3, and having the head blocks 4. I also provide the brace bars 5, secured by the nuts 6 in the end frames.

In the end frames 1 and 2, I provide bearings 7 which are mounted in the openings 8 of the end frames 1 and 2. In these bearings, I mount a shaft 9, on which is securely mounted a roll 10.

I further provide a series of supporting rolls 12, 13 and 14, which are securely mounted on the shaft 15, 16 and 17, respectively.

These shafts are journaled in the end frames 1 and 2.

Located intermediately between the upper roll 10 and the lower or supporting rolls 12, 13 and 14, I provide and place the forming rolls 18 and 19. These rolls 18 and 19 are floating rolls, and are supported by the 70 rolls 12, 13 and 14, and are held in proper alignment by guide lugs 20 and 21, which lugs are fastened to the end frames 1 and 2, respectively.

In order to curve or bend metal plates as 75 22, of varying thicknesses and to varying curves, or radii, I furnish adjustment means for the rolls. To accomplish this, I provide adjusting screws 23 and 24, which are mounted in the head blocks 4, the lower 80 extremities of said screws 23 and 24, impinge or press downwardly on the journal boxes or bearings 7, and springs 25 are employed for the purpose of holding said bearings 7 in the proper relation against the 85 screws 23 and 24. These springs 25 are mounted in recesses 26, in the end frames 1 and 2.

At the upper ends of screws 23 and 24, I securely mount sprocket wheels 27, over 90 which passes the sprocket chain 28. In order to adjust the screws 23 and 24, I provide a hand wheel 29, which is securely mounted at the upper extremity of the screw 23, and it will be seen that by turning said hand wheel, the sprockets 27 will both revolve through the medium of the chain 28, and a spacing bar 30 is to prevent any bind 95 which might take place, caused by said adjustment.

A feeding board or table 31 is secured between the end frames 1 and 2. A guide 32

is supported on an adjusting bar 33, which is slidably mounted in the bracket 34, which, in turn, is secured to the end frame 1, by a wing nut 35, and allows for adjustment of 5 guide 32, in order to adjust it back and forth.

The machine is driven as follows: to wit: The drive pulley 36 is mounted on one end of shaft 37, the other end of said shaft having 10 mounted thereon a worm 38, and said shaft 37 is mounted in bearings 39. The worm 38 drives the worm wheel 40, which is mounted securely to one end of the shaft 16, the opposite end of said shaft has securely mounted 15 thereon, a gear 41, which has an extension hub 42, which bears against the side frame 1 and allows a clearance space for the gears 43 and 44, said gears being mounted on the shafts 15 and 17, respectively. In order to 20 revolve the gears 43 and 44, I provide idler gears 45 and 46, which are mounted on stud shafts 47 and 48; these gears 45 and 46, have wide faces as shown and said faces engage with the gear 41, and are revolved by said 25 gear 41. It will be seen that the gears 43 and 44 are in turn revolved by idler gears 45 and 46. I also provide an idler gear 49, which is mounted on stud shaft 50, which idler engages gear 44 through which it receives its 30 action and also engages with the gear 51, which is mounted on shaft 9, imparting action to said gear 51.

On the roll 13 at points 52, I mount the gears 53 and 54; the gear 54 engages a gear 35 55 which is mounted at one end of the floating roll 19 and the gear 54 engages a gear 56 which is mounted on the floating roll 18. It will be noted that the gears 53 and 54 are 40 at opposite ends of the machine, and the purpose of this construction is to allow the center of these floating rolls 18 and 19 to be brought very closely together, in order to produce a proper curvature on the plate 22 and thus avoiding any tending to make the 45 plate flat during its passage through the rolls.

In order to allow these gears to operate, I provide a clearance space 57, between the frames 1 and 2, and the rolls 12, 14, 18, 19 50 and 10.

The guide lug 20 forms a guide for roller 18 which makes up for the space 57 adjoining frame 1 and the guide lug 21, makes up for spaces 57 for roller 19 along side of the 55 frame 2.

As pulley 36 is revolved, the worm 38 and wheel 40 also revolves, turning shaft 16 which carries the gears 41, 53, and 54; the gear 41 engages idlers 45 and 46, which in 60 turn revolve the gears 43 and 44; the supporting rolls 12, 13 and 14 are thus revolved in one direction while the gears 55 and 56, of the floating rolls 18 and 19 engage the gears 53 and 54, of the supporting roll 13; 65 said floating rolls 18 and 19 are thus also re-

volved. As the gear 44 engages the floating roll 19 the gear 51 which is of the upper roll 10, is revolved.

It will be seen that the roll 10 and the floating rolls 18 and 19, are revolved against each other as in the ordinary wringer, so as to draw the plate 22 through while the three supporting rolls 12, 13 and 14 are revolved the same direction so as to impart to the floating rolls a similar directional rotation. 70

In the above description I have set forth a preferred form and means of carrying my invention into effect, and while I have described one specific form of making my machine for bending plates, I do not wish to be limited to the exact construction herein set forth, it being evident that I may modify and change the same to some extent without departing from the principle of the invention, and I wish to be understood as claiming 85 any modifications or changes which fall within the scope of this specification and claims.

What I claim as new and my invention and desire to secure by Letters Patent is:

1. A metal bending machine, including a frame, supporting rollers journaled in said frame, floating rollers carried by the supporting rollers, means for driving the supporting rollers all in the same direction, and a bending roller journaled in the frame and spaced from the floating rollers. 90

2. A metal bending machine, including a frame, supporting rollers journaled in said frame, means for driving all of the supporting rollers in the same direction, floating rollers resting on and carried by the supporting rollers, means for driving the floating rollers in the same direction from said supporting rollers, and a bending roller journaled in the frame and spaced from the floating rollers. 100

3. A metal bending machine, including a frame, three supporting rollers journaled in the frame, means for driving said supporting rollers all in the same direction, a pair of floating rollers resting upon and carried by the supporting rollers, a single bending roller journaled in the frame, and means for driving said bending roller. 110

4. A metal bending machine, including a frame having side bars, supporting rollers and a bending roller journaled in the side bars of the frame, means for driving said rollers, and floating rollers arranged between the supporting rollers and the bending roller, resting on the supporting rollers and driven from the latter. 120

5. A metal bending machine, including a frame, supporting rollers having shafts journaled in the ends of the frame, means for driving one of said rollers in one direction, means for driving the other rollers from the last mentioned roller, and in the same direction as the latter, floating rollers 130

resting upon the supporting rollers, means for driving the floating rollers in an opposite direction from the supporting rollers, a bending roller journaled in the frame and arranged above the floating rollers, and means for driving the bending roller from one of the supporting rollers.

6. A metal bending machine, including a frame having end bars, supporting rollers having shafts journaled in the end bars, means for rotating one of said shafts for driving the roller of the latter in one direction, means for driving the other rollers from the driven roller, and in the same di-

rection as the latter, floating rollers resting on and carried by the supporting rollers, means for driving the floating rollers from said driven roller, and in a direction opposite to that of the latter, adjustable journals movably mounted in the end bars, a bending roller having a shaft journaled in the adjustable journals, and means for driving the last mentioned shaft from one of the supporting rollers.

In testimony whereof, I affix my signature at Cincinnati, Ohio, this 17th day of December, 1925.

FREDERICK J. WERMES.
